Rufus Humphrey, of Victor, N. York
Letters Patent

The schedule referred to in these Letters Patent, and making part of the same, containing a description in the words of the said Rufus Humphrey, himself, of his improvement in the Threshing Machine -

To all to whom these presents shall come: Be it known that J. Rufus Humphrey, of the Town of Victor, in the County of Ontario, and State of New York, have invented a new and useful improvement in the machine for threshing wheat, rye, rice, and other small grain; and that the following is a full and exact description of the construction and operation of the said machine as improved: It differs from all machines of this kind now in use in the simplicity of its machinery, and the cheapness of its construction; it being designed to be propelled by one horse, the horse turns by the ordinary lever power, a large horizontal wheel, around which is a band, which connects the large horizontal wheel just mentioned, with an upright wheel, on the bottom of which is a set of cogs; one revolution of this large wheel turns the leper one six times - in the passage of the band which connects these two wheels, are two other wheels against which the band crowds; in that way is always kept in place - if the band stretches or slackens, a wedge throws these two small wheels closer together, and compresses the band around the large wheel -

The cog wheel turns in one revolution (by making into a set of cogs of the same size) a shaft placed horizontally under it, eight times: this shaft by a band in the ordinary fashion turns the cylinder of the threshing machine, in this cylinder the cogs are placed double, one behind the other, and close together; the cylinder revolving eight or nine times as the shaft before mentioned turns once, the rows of teeth on the cylinder, play between similar teeth fixed in the same manner on a bed piece; the cylinder and bed piece are both covered with sheet iron, and the teeth are driven through this, between this bed piece, and the cylinder, the straw to be threshed, passes.

The machine is fed by an airon leading to the cylinder in the common way.
